CODED RAILWAY SIGNALING APPARATUS

Arthur L. Jerome, Edgewood, Pa., assignor to The Union Switch & Signal Company, Swissvale, Pa., a corporation of Pennsylvania

Application December 31, 1943, Serial No. 516,363

11 Claims. (Cl. 246—38)

My invention relates to railway signaling apparatus and particularly to improved apparatus of the type shown in application for Letters Patent of the United States, Serial No. 512,723, filed December 3, 1943, by Crawford E. Staples, for use in a single track stretch to supply coded alternating current cab signal control energy to the rails of track sections equipped with track circuits employing steady energy.

In application for Letters Patent of the United States, Serial No. 412,279, of James J. Van Horn, now United States Patent No. 2,344,333, dated March 14, 1944, there is shown a signaling system adapted for use in single track stretches over which traffic moves in both directions. This system employs coded energy to control traffic, and most of the track sections are provided with track circuits employing coded energy, but in some cases, such as the approach sections to a highway crossing, the track sections are provided with track circuits employing steady energy, while the coded traffic governing energy is transmitted around these sections by means of a line circuit.

In track stretches through which are operated locomotives equipped with cab signal apparatus, it is necessary to provide means to supply coded alternating current of appropriate code frequency to the rails of the track sections equipped with track circuits employing steady energy.

In the above-identified application of Crawford E. Staples, there is shown means employing two coding relays, one for each direction of traffic, for supplying coded alternating current to the rails of the approach sections to a highway crossing, while these coding relays are operated by coded energy supplied to the line circuit extending around the approach sections.

It is an object of this invention to provide improved alternating current supply means of the type described and employing a single coding relay which serves for both directions of traffic.

A further object of the invention is to provide improved means of the type described which employs a coding relay responsive to energy of one polarity only and is reversibly connected across the line wires so as to be operated by energy supplied to the line wires even though energy of one polarity is supplied to the line wires when traffic is established for one direction, and energy of the other polarity is supplied to the line wires when traffic is established for the other direction.

Another object of the invention is to provide improved means of the type described which em-

ployes a single coding relay and is arranged so that on movement of a train through the track stretch in one direction this coding relay is connected across the line wires so as to be operated by energy supplied to the line wires at one end thereof, and so that on movement of a train through the track stretch in the opposite direction the coding relay is connected across the line wires so as to be operated by energy supplied to the line wires at the other end thereof.

Other objects of the invention and features of novelty will be apparent from the following description taken in connection with the accompanying drawing.

15 I shall describe two forms of railway signaling apparatus embodying my invention and shall then point out the novel features thereof in claims.

16 In practicing my invention, I provide a coding relay at the highway intersection and provide means governed by the approach section track relays for reversibly connecting the coding relay across the line wires extending around the approach sections. In addition, I provide means 20 governed by the approach section track relays for controlling the coded alternating current supplied on operation of the coding relay so that this energy is supplied to the proper track transformers on movement of a train through the 25 track stretch in either direction.

30 In the drawing, the single figure is a diagram showing a stretch of railway track equipped with one form of signaling apparatus embodying my invention.

35 Referring to the drawing, there is shown therein a stretch of single track railroad through which are operated in both directions locomotives equipped with cab signal apparatus responsive to flow of coded alternating current in the 40 track rails. The construction and operation of the locomotive cab signal apparatus is not a part of this invention and the locomotive equipment may be constructed as shown in Letters Patent of the United States No. 1,986,679 to L. V. Lewis.

45 The track stretch shown in the drawing is a part of a single track stretch equipped with traffic governing signaling apparatus of the type shown in application, Serial No. 412,279, of James J. Van Horn. In the system shown in the 50 Van Horn application, each track section in the track stretch, except for the portions of the track stretch where short detector track circuits are required, is equipped with two track circuits, one for each direction of traffic. Means are provided to at times supply steady energy to either end

of the track stretch, while the track circuits are arranged so that when the track stretch is vacant this steady energy is cascaded from one section to another throughout the track stretch to energize traffic locking means at the other end of the stretch and thus permit the direction of traffic to be changed. In addition, there are means at each end of the track stretch effective after the stretch has been conditioned for either direction of traffic to supply coded energy to the section at the exit end of the track stretch, and the track circuit apparatus for each section is arranged so that this coded energy is cascaded from one section to another to the entrance end of the track stretch to control the signal at the entrance end of the stretch.

As shown in Fig. 4 of the Van Horn application, where a highway crossing is encountered, track sections employing steady energy track circuits are provided on either side of the intersection to control the crossing signals, while a line circuit is provided to carry around these sections the steady and coded energy employed in the rest of the track stretch.

The portion of the track stretch shown in the drawing of this application includes an intersection with a highway and this crossing is protected by crossing signals XS, while the track stretch is divided into suitable track sections for controlling the crossing signals.

This invention is directed to the means for supplying coded alternating current to the short section which includes the highway crossing, and to the approach sections at either side of this section. This invention is not concerned with the apparatus at other points in the track stretch or at the ends of the single track stretch except insofar as the equipment of this invention is intended to operate in conjunction with that apparatus, and the equipment at those locations may be arranged as shown in the Van Horn application. In order to simplify the disclosure and facilitate understanding of my invention, only the equipment for the approach sections and the adjacent ends of the adjoining sections has been shown in the drawing.

The rails 1 and 2 of the track stretch are divided by insulated joints 3 into a number of track sections each of which is identified by the reference character T with a distinguishing prefix which also identifies the apparatus associated with that section.

To facilitate description of the equipment and its operation, it will be assumed that the right-hand end of the track stretch is east and that the left-hand end of the track stretch is west so that train movements from left to right are eastbound and train movements from right to left are westbound.

The intermediate track section ICT is a short section which includes the highway intersection, and this section has at one side the eastbound approach section IBT, and at the other side the westbound approach section IDT. The track relays IBTR and IDTR of the approach sections cooperate with track relay ICTR of the intermediate section ICT to control directional stick relays WSR and ESR and the crossing signal control relay XR. However, the invention is not limited to the use of this form of crossing signal control apparatus and an interlocking relay of well-known construction, or other appropriate apparatus, may be employed to control the crossing signals.

The approach sections and the intermediate

sections are provided with track circuits employing steady energy. Each of these track circuits includes a track battery connected across the section rails at one end of the track section and a track relay, designated TR with an appropriate prefix, connected across the section rails at the other end of the section.

Each track section in the track stretch is provided with a track transformer at each end of the track section. These track transformers are designated TT with an appropriate prefix to indicate the track section with which the transformer is associated and the end of the section at which it is located.

15 The track transformers at the ends of sections IBT, ICT and IDT at which the track batteries are located have their secondary windings connected in series with the track batteries, while these secondary windings are of relatively low resistance so as not to unduly reduce the supply of energy from the batteries to the section rails.

20 The track transformers located at the track relay ends of the sections have their secondary windings connected in multiple with the track relays, while resistors are included in series with the track transformer secondary windings to restrict flow of track circuit energy in these windings. The track relay windings have such high impedance to alternating current that little energy from the track transformers flows in the relay windings.

25 As explained in the application of James J. Van Horn, each of the track sections IBT and ICT is provided with two track circuits, one for each direction of traffic. Each track circuit for each of these track sections includes a code following track relay at one end of the track section and a track battery at the other end of the section, while at each end of the section there is a coding relay CTM having contacts controlling connection of the associated track battery and track relay with the section rails.

30 35 The equipment at the highway crossing includes a coding relay XCTM which operates as hereinafter explained to cause coded alternating current to be supplied to section ICT, and to section IBT or IDT.

40 45 The coding relays XCTM, IEACTM and IWECTM are of the magnetically biased type the contacts of which normally occupy their released position and are picked up only when energy flows through the relay winding in a given direction. As shown in the drawing, the relay XCTM is arranged so that its contact picks up only when the positive terminal of the source is connected to the left-hand terminal of the relay winding, while the relays IEACTM and IWECTM are arranged so that their contacts pick up only when the positive terminal of the source is connected to the right-hand terminal of the relay winding.

50 55 The relays and other equipment except the track relays are supplied from suitable sources of direct current, such as storage batteries, not shown, located at appropriate points in the track stretch. The positive and negative terminals of these sources are designated B and C, respectively, in the drawing.

60 65 The alternating current supplied to the track transformers may be supplied from any suitable source, not shown, the terminals of which are designated BX and CX in the drawing.

70 75 The equipment is shown in the condition

which it assumes when the track stretch is vacant and steady energy is supplied at the east end of the track stretch. As explained in the Van Horn application, steady energy supplied at the east end of the track stretch is cascaded from one track section to another to the west end of the track stretch to energize traffic locking means at that point.

As steady energy is supplied to the east end of section 7ET, this energy feeds over back contacts of coding relay 7WEACTM and holds the contacts of track relay 7EETR picked up so that its contacts 10 and 11 connect line wires 14 and 15 to the terminals of a source of direct current. Accordingly, energy is supplied from terminal B over contact 11, wire 15, front contact 16 of track relay 7DTR, front contact 17 of track relay 7CTR, front contact 18 of track relay 7BTR, back contact 21 of track relay 7WATR, winding of coding relay 7WEACTM from right to left, back contact 20 of track relay 7WATR, line wire 14, front contact 22 of relay 7BTR, front contact 23 of relay 7CTR, front contact 24 of relay 7DTR, and front contact 10 of track relay 7EETR to terminal C. The direction of flow of energy through the winding of coding relay 7WEACTM is proper to pick up the relay contacts 25 and 26 and they are picked up to connect track battery 7EATB and track transformer 7EATT across the rails of section 7AT and to disconnect the track relay 7WATR from the section rails. Accordingly, steady energy is supplied from the battery 7EATB to the rails of section 7AT and this energy picks up the track relay not shown at the west end of this section and causes the supply of steady energy to be repeated throughout the other track sections to the west end of the track stretch.

As the track stretch is vacant, the track relays 7BTR, 7CTR and 7DTR are picked up so energy is supplied to relay XR over the circuit including front contact 27 of relay 7CTR, front contact 28 of relay 7DTR, and front contact 29 of relay 7BTR, so contact 30 of relay XR is picked up to prevent operation of the crossing signals XS.

At this time, relays WSR and ESR are released, while relay XCTM is deenergized and its contact 32 is released.

If it is desired to permit a westbound train to pass through the track stretch, means, not shown, at the right-hand or east end of the track stretch are operated to permit clearing of the westbound signal at that point and to cut off the supply of steady energy to the east end of the stretch, when the supply of steady energy to the stretch is cut off, the track relay for each section releases and cuts off the supply of steady energy to the adjoining section so the supply of steady energy is cut off from the various sections in succession throughout the track stretch, while the contacts of the coding relays are released and connect the track relays across the section rails.

At this time, therefore, relay 7EETR releases and cuts off the supply of steady energy to the line wires 14 and 15 so relay 7WEACTM releases and cuts off the supply of energy from battery 7EATB and transformer 7EATT to the rails of section 7AT and connects track relay 7WATR across the section rails.

When the supply of steady energy at the west end of the track stretch is cut off, apparatus, not shown, at that location causes coded energy of suitable code frequency, such as 75 or 180 code

frequency, to be supplied to the west end of the track stretch.

On the supply of coded energy to the west end of the track stretch, coded energy is cascaded through 5 the successive track sections to section 7AT and coded energy is supplied over back contacts 25 and 26 of relay 7WEACTM to track relay 7WATR. Accordingly, track relay 7WATR follows code, and during the picked-up periods of the relay its contacts 20 and 21 connect wires 14 and 15 across a source of direct current with wire 14 connected to the positive terminal of the source. Energy supplied to the line wire feeds over back contacts 10 and 11 of relay 7EETR and through the winding 15 of coding relay 7WEACTM so that it operates to cause coded energy to be supplied from track battery 7WETB and track transformer 7WETT to the rails of section 7ET, while the track circuit apparatus, not shown, at the east end of section 20 7ET causes coded energy to be supplied to the adjoining section.

It is to be observed that when energy is supplied to line wires 14 and 15 by operation of relay 7EETR, the positive terminal of the source 25 is connected to wire 15, and the energy supplied to the line wires is of the polarity effective to operate coding relay 7WEACTM, while when energy is supplied to line wires 14 and 15 by operation of relay 7WATR, the positive terminal of the source is connected to wire 14 and the energy supplied to the line wires is of the polarity effective to operate coding relay 7WEACTM. The use of different polarities of energy in the line circuit for different directions of traffic is advantageous as it prevents improper operation of the coding relays if the track relay contacts overlap.

For example, if the front and back contacts of track relay 7EETR are out of adjustment so that movable contacts 10 and 11 both engage their front contacts before being disengaged from their back contacts, energy will be supplied from the source at that point to the coding relay 7WEACTM, but the polarity of this energy is such that it will not pick up the contacts of relay 7WEACTM. The relay 7WEACTM, therefore, remains released and does not cause coded energy to be supplied to section 7ET which might interfere with the established direction of traffic.

Similarly, relay 7WEACTM will not respond to energy supplied thereto in the event of overlapping contacts on the track relay 7WATR.

When a westbound train enters section 7ET, the cab signal apparatus on the locomotive is 55 operated by coded alternating current supplied to the section rails as a result of operation of coding relay 7WEACTM.

When the train advances into section 7DT, track relay 7DTR releases and its contacts 16 and 60 24 interrupt the circuits of line wires 15 and 14 to thereby cut off the supply of energy to coding relay 7WEACTM so that it ceases to supply energy to the rails of section 7ET and remains released so that track relay 7EETR is connected 65 across the section rails.

On release of relay 7DTR, the coding relay XCTM is connected across the line wires 14 and 15 so as to be operated by coded energy supplied to these wires as a result of coding operation of relay 7WATR. At this time, energy is supplied to relay XCTM over the circuit which is traced from terminal B of the source over front contact 20 of relay 7WATR, wire 14, front contact 22 of relay 7BTR, front contact 23 of relay 7CTR, back contact 24 of relay 7DTR, winding of relay

XCTM from left to right, back contact 16 of relay 1DTR, front contact 17 of relay 1CTR, front contact 18 of relay 1BTR, wire 15, and front contact 21 of relay 1WATR to terminal C. The polarity of the energy supplied to relay XCTM is proper to operate the relay and the relay contact 32 operates at the rate determined by the rate of operation of relay 1WATR.

On coding operation of relay XCTM, coded alternating current is supplied from back contact 43 of relay ESR to the transformer 1WCCT and also over front contact 45 of relay 1CTR to the transformer 1WDTT so that coded alternating current is supplied to the rails of section 1DT to operate the locomotive cab signal apparatus while the locomotive is in section 1DT. Prior to picking up of relay WSR coded alternating current is also supplied over its back contact 44 to transformers 1EBTT and 1ECTT.

In addition, on release of track relay 1DTR, its contact 28 interrupts the circuit of relay XR so that contact 30 of relay XR releases and establishes the circuit of the crossing signals XS and they operate to warn users of the highway of the approach of the train.

On release of track relay 1DTR, a pick-up circuit is established for relay WSR and includes front contact 34 of track relay 1BTR, back contact 35 of track relay 1DTR, and back contact 36 of relay ESR.

Accordingly, relay WSR picks up and its contact 44 cuts off the supply of coded alternating current to the transformers 1EBTT and 1ECTT, while contacts 38 and 41 of relay WSR connect relay XCTM across line wires 14 and 15 at a point intermediate the contacts of relays 1BTR and 1CTR in these line wires to thereby continue operation of relay XCTM after the train advances into section 1CT and track relay 1CTR releases. At this time, the left-hand terminal of the winding of relay XCTM is connected over back contact 37 of relay ESR and front contact 38 of relay WSR to the wire 14, while the other terminal of the winding of relay XCTM is connected over back contact 40 of relay ESR and front contact 41 of relay WSR to wire 15 so the energy supplied from the line wires is of the proper polarity to operate the relay XCTM.

At this time, coded alternating current continues to be supplied over back contact 43 of relay ESR to the transformers 1WCCT and 1WDTT, that is, to the transformers appropriate for movement of a westbound train through the track stretch.

From the foregoing, it will be seen that when a westbound train enters section 1DT, relay XR releases to initiate operation of the crossing signals, while relay XCTM is connected across the wires 14 and 15 so as to be operated by coded energy supplied to these line wires over the front contacts of relay 1WATR and operates to supply coded alternating current to the track transformers and thus to the track rails to operate the locomotive cab signal equipment. In addition, when a westbound train enters section 1DT, relay WSR picks up to cut off the supply of energy to the track transformers for eastbound traffic, and to establish a circuit to continue operation of relay XCTM after the train advances into section 1CT.

When the train advances into section 1CT, track relay 1CTR releases and its contact 45 interrupts the circuit for supplying coded alternating current to the track transformer 1WDTT, while energy continues to be supplied to trans-

former 1WCTT and thus to the rails of section 1CT to operate the locomotive cab signal apparatus while the locomotive is in this section.

On release of track relay 1CTR, its contacts 17 and 23 additionally interrupt the circuit of the line wires 15 and 14 to thereby prevent coded energy supplied to these wires over contacts of relay 1WATR from reaching relay 1WECTM on picking up of relay 1DTR. On release of relay 1CTR, the originally traced circuit for relay XCTM is interrupted, but this relay continues to be supplied with coded energy from line wires 14 and 15 over the connections established by relay WSR.

15 In addition, on release of relay 1CTR, a stick circuit is established for relay WSR and includes back contact 27 of relay 1CTR, and front contact 46 of relay WSR.

When the train advances into section 1BT, the cab signal apparatus on the locomotive is operated by coded alternating current supplied to the rails of section 1BT from transformer 1WBTT, while coded energy is supplied to the transformer 1WBTT over the circuit including contact 47 of track relay 1WATR.

When the train enters section 1BT, track relay 1BTR releases and its contacts 18 and 22 interrupt line wires 15 and 14 so that coded energy is no longer supplied to coding relay XCTM and the contact 32 of this relay remains released and energy is no longer supplied to either track transformer 1WCCT or 1WDTT. Release of contacts 18 and 22 also prevents energy supplied to the line wires 14 and 15 on picking up of track relay 1EETR from feeding over back contacts of track relay 1WATR to coding relay 1EACTM with resultant interruption of the coding operation of track relay 1WATR.

When the train advances into section 1AT, the 40 track relay 1WATR ceases to follow code and its contacts remain released to connect line wires 14 and 15 to coding relay 1EACTM, while contact 41 of relay 1WATR interrupts the supply of energy to track transformer 1WBTT.

As explained in the Van Horn application, steady energy may be supplied to the track stretch behind the train, and this steady energy will be cascaded throughout the track stretch as each track section is vacated, but only after an impulse of coded energy has been supplied over the section rails. Accordingly, when section 1ET is vacated, relay 1EETR remains released and connects line wires 14 and 15 to relay 1WECTM.

When the train vacates section 1DT, track relay 1DTR picks up and energy is supplied to relay WSR over the stick circuit which includes front contact 35 of relay 1DTR, back contact 34 of relay 1BTR, and front contact 48 of relay WSR. The energy supplied to relay WSR over this circuit keeps relay WSR picked up after section 1CT is vacated and relay 1CTR picks up and its contact 27 interrupts the previously traced stick circuit for relay WSR.

When section 1CT is vacated and track relay 1CTR picks up, energy is supplied to relay XR over the circuit which includes front contact 27 of relay 1CTR, front contact 28 of relay 1DTR, and front contact 50 of relay WSR, so relay XR picks up to discontinue operation of the crossing signals XS.

70 When the train vacates section 1BT, track relay 1BTR picks up and its contact 34 interrupts the stick circuit for relay WSR, while its contact 29 completes the circuit including front contact 28 of relay 1DTR and front contact 27 of relay

ICTR for energizing relay XR so it remains picked up to prevent operation of the crossing signals XS. On release of relay WSR, its contacts 46 and 48 additionally interrupt the stick circuits for the relay, while its contacts 41 and 38 interrupt the circuit of coding relay XCTM, and its contact 44 establishes the circuit over which coded alternating current is supplied to transformers 1ECTT and 1EBTT on operation of coding relay XCTM.

When track relay 1BTR picks up, its contacts 18 and 22 complete the circuit of line wires 15 and 14 so that when the train vacates section 1AT and coded energy supplied over the rails of that section picks up relay 1WATR, an impulse of energy is supplied over the line wires 14 and 15 to relay 1WEACTM and it causes an impulse of energy to be supplied to the rails of section 1ET. This energy may cause the equipment at the right-hand end of section 1ET to operate to supply steady energy to the rails of section 1ET, and this energy feeds over back contacts of relay 1WEACTM and picks up the contacts of relay 1EETR and thus causes steady energy to be supplied to the line wires 14 and 15. This energy feeds to relay 1EACTM and causes steady energy to be supplied to the rails of section 1AT.

If, after the westbound trains vacate the track stretch, the steady energy supplied at the east end of the track stretch is cut off and coded energy substituted therefor, this coded energy will be cascaded throughout the track stretch to clear the signal at the west end of the stretch and permit an eastbound train to enter the stretch.

On the supply of coded energy to the east end of section 1ET, energy feeds over back contacts of coding relay 1WEACTM to track relay 1EETR and operates it so that its contacts 10 and 11 cause coded energy to be supplied to line wires 14 and 15 with the result that coded energy is supplied to coding relay 1EACTM and operates it to supply coded energy to the rails of section 1AT. In addition, when track relay 1EETR is operated by coded energy, coded alternating current is supplied over contact 52 of relay 1EETR to transformer 1EDTT and therefrom to the rails of section 1DT at the right-hand or exit end of the section.

When an eastbound train enters section 1BT, the track relay 1BTR releases and its contacts 18 and 22 interrupt the supply of energy to coding relay 1EACTM so that it ceases to supply coded energy to the rails of section 1AT, while its contacts remain released and connect track relay 1WATR across the section rails.

On release of track relay 1BTR, the coding relay XCTM is connected across the line wires 14 and 15 so as to be operated by coded energy supplied to these line wires by relay 1EETR. At this time, the left-hand terminal of the winding of relay XCTM is connected over back contact 18 of relay 1BTR to wire 15, while the other terminal of the winding of relay XCTM is connected over back contact 22 of relay 1BTR to wire 14. On coding operation of relay 1EETR, the positive terminal of the source is connected to wire 15 so the energy supplied to relay XCTM is of the proper polarity to operate the relay and its contact 32 operates to supply coded alternating current to the track transformers at the highway intersection so that coded alternating current is supplied to the rails of section 1BT to operate the cab signal apparatus on the locomotive while it is in that section.

- In addition, on release of relay 1BTR, energy is supplied to relay ESR over the circuit which includes front contact 35 of relay 1DTR, back contact 34 of relay 1BTR, and back contact 48 of relay WSR. Accordingly, the contacts of relay ESR pick up so that its contact 43 cuts off the supply of coded alternating current to the transformers 1WCTT and 1WDTT from which energy is supplied to the rails of the track stretch on movement of westbound trains through the track stretch. At this time, coded alternating current continues to be supplied over back contact 44 of relay WSR to the transformers 1EACT and 1EBTT.
- 15 In addition, on picking up of relay ESR, its contacts 37 and 40 connect relay XCTM with the line wires 14 and 15 at a point intermediate the contacts of relays 1CTR and 1DTR so that relay XCTM continues to be operated by coded energy from line wires 14 and 15 after the train enters section 1CT and relay 1CTR releases. On picking up of relay ESR, the left-hand terminal of the winding of relay XCTM is connected over back contact 38 of relay WSR and front contact 37 of relay ESR to wire 15, while the other terminal of the winding of relay XCTM is connected over back contact 41 of relay WSR and front contact 40 of relay ESR to wire 14, and the energy supplied to relay XCTM is of the proper polarity to operate the relay.

When the train enters section 1CT, track relay 1CTR releases and its contact 53 interrupts the circuit of track transformer 1EBTT but does not affect the circuit of the transformer 1ECTT so that coded energy continues to be supplied to the rails of section 1CT at the exit end of the section to operate the locomotive cab signal apparatus while the locomotive is in section 1CT.

On release of track relay 1CTR, its contacts 40, 17 and 23 additionally interrupt the circuit of line wires 15 and 14, while its contact 27 establishes a stick circuit for relay ESR which includes front contact 55 of relay ESR.

When the train advances into section 1DT, the locomotive cab signal equipment is operated by coded alternating current supplied from transformer 1EDTT to the rails of section 1DT as a result of operation of track relay 1EETR.

When the train enters section 1DT, track relay 1DTR releases and its contacts 16 and 24 interrupt the supply of energy to coding relay XCTM so that its contact 32 remains released and ceases to cause coded energy to be supplied to the transformers 1ECTT and 1EBTT.

When the train advances into section 1ET, track relay 1EETR ceases to follow code and remains released so that energy is not supplied to the line wires 14 and 15, while contact 52 interrupts the circuit of transformer 1EDTT.

As explained in the application of James J. Van Horn, steady energy may be supplied to the track stretch behind the train, and this steady energy is cascaded from one section to another as the train vacates each section and an impulse of coded energy is supplied over the section rails. Accordingly, when the train vacates section 1AT, relay 1WATR remains released and its contacts 20 and 21 connect line wires 14 and 15 to the coding relay 1EACTM.

When the train vacates section 1BT, track relay 1BTR picks up and energy is supplied to relay ESR over the circuit including front contact 34 of relay 1BTR, back contact 35 of relay 1DTR, and front contact 36 of relay ESR, and the energy supplied over this circuit keeps relay ESR picked

up after relay **1CTR** picks up to interrupt the stick circuit which it controls for relay **ESR**.

When section **ICT** is vacated and track relay **1CTR** picks up, energy is supplied over front contact **27** of track relay **1CTR**, front contact **56** of relay **ESR** and front contact **29** of relay **1BTR** to relay **XR** so that contact **30** of relay **XR** picks up to discontinue operation of the crossing signals **XS**.

When the train vacates section **1DT**, track relay **1DRT** picks up and its contact **35** completes the originally traced circuit for relay **XR**, and interrupts the stick circuit for relay **ESR** so the contacts of relay **ESR** release. In addition, contacts **16** and **24** of relay **1DRT** complete the circuits of line wires **15** and **14** so that, when section **IET** is vacated and relay **1EETR** picks up, coded energy will be supplied over the line wires, while when relay **1WATR** is picked up by steady energy supplied over the rails of section **1AT**, steady energy will be supplied over the line wires **14** and **15** to relay **1WECTM** and thus cause steady energy to be repeated throughout the track stretch.

From the foregoing, it will be seen that, when the track stretch is vacant, coded and steady traffic governing energy may be supplied between the track sections at the sides of the approach sections over the line wires extending around the approach sections and that at such times the coding relay **XCTM** is not connected with the line wires and does not interfere with the coding relays at the ends of the line wires. It will be seen that, when the stretch is conditioned for movement of traffic in either direction, coded energy of appropriate code frequency is supplied to the line wires, while on entrance of a train into either approach section the supply of energy over the line wires to the coding relay at the entrance end of the line wires is cut off and the coding relay **XCTM** is connected across the line wires so as to be operated by the energy supplied to the exit end of the line wires. In addition, when the coding relay **XCTM** is being operated by coded energy, the energy supplied over the contact of the coding relay is supplied to the track transformers proper for the direction of traffic in which the train is moving. As soon as the train vacates the track section which includes the highway crossing, operation of coding relay **XCTM** ceases, but supply of energy over the line wires to the coding relays at the ends of the line circuit continues to be prevented until the train vacates both approach sections.

Although I have herein shown and described only one form of railway signaling apparatus embodying my invention, it is obvious that numerous changes and modifications may be made therein within the scope of the appended claims without departing from the spirit and scope of my invention.

Having thus described my invention, what I claim is:

1. In a cab signal energy supply means for use in a stretch of railway track over which may move in either direction locomotives equipped with cab signal apparatus responsive to flow of coded alternating current in the track rails, the rails of said track stretch being divided by insulated joints into an intermediate section having a first approach section at one side and a second approach section at the other side, said intermediate and approach sections each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of the approach sections remote from said intermediate section, said traffic governing apparatus being effective when the stretch is conditioned to permit traffic to move from the first to the second approach section to cause coded energy to be supplied to said line wires at the end thereof remote from the first section and being effective when the stretch is conditioned to permit traffic to move from the second to the first approach section to cause coded energy to be supplied to said line wires at the end thereof remote from the second section, in combination, a coding relay located adjacent said intermediate section and controlling the supply of coded alternating current to the rails of said intermediate section and to the rails of said approach sections at the ends thereof adjacent said intermediate section, means controlled by the track relays of said first approach and intermediate sections for supplying from the line wires to said coding relay energy supplied to the line wires at the end thereof remote from said first approach section, and means controlled by the track relays of said second approach and intermediate sections for supplying from the line wires to said coding relay energy supplied to the line wires at the end thereof remote from said second section.

when said second approach or intermediate section is occupied by a train moving from said second to said first approach section to connect said coding relay across said line wires so as to be operated by energy supplied to the line wires at the end thereof remote from the second approach section.

3. In cab signal energy supply means for use in a stretch of railway track over which may move in either direction locomotives equipped with cab signal apparatus responsive to flow of coded alternating current in the track rails, the rails of said track stretch being divided by insulated joints into an intermediate section having a first approach section at one side and a second approach section at the other side, said intermediate and approach sections each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of the approach sections remote from said intermediate section, said traffic governing apparatus being effective when the stretch is conditioned to permit traffic to move from the first to the second approach section to cause coded energy to be supplied to said line wires at the end thereof remote from the first section and being effective when the stretch is conditioned to permit traffic to move from the second to the first approach section to cause coded energy to be supplied to said line wires at the end thereof remote from the second section, in combination, a coding relay located adjacent said intermediate section and controlling the supply of coded alternating current to the rails of said intermediate section and to the rails of said approach sections at the ends thereof adjacent said intermediate section, means effective when said first approach or intermediate section is occupied by a train moving from the first to the second approach section to connect said coding relay across the line wires so that the coding relay is operated by energy supplied to the line wires at the end thereof remote from the first approach section while preventing flow of energy between the portions of the line wires on opposite sides of the intermediate section, and means effective when said second approach or intermediate section is occupied by a train moving from the second to the first approach section to connect said coding relay across the line wires so that the coding relay is operated by energy supplied to the line wires at the end thereof remote from the second approach section while preventing flow of energy between the portions of the line wires on opposite sides of the intermediate section.

4. In cab signal energy supply means for use in a stretch of railway track over which may move in either direction locomotives equipped with cab signal apparatus responsive to flow of coded alternating current in the track rails, the rails of said track stretch being divided by insulated joints into an intermediate section having a first approach section at one side and a second approach section at the other side, said intermediate and approach sections each being provided with a track circuit including a track relay, said track stretch being equipped with traffic governing apparatus for conditioning the track stretch for one direction of traffic or the other

5. and including a pair of line wires substantially coextensive with said approach sections and over which coded energy may be transmitted between the track sections at the ends of the approach sections remote from said intermediate section, said traffic governing apparatus being effective when the stretch is conditioned to permit traffic to move from the first to the second approach section to cause coded energy of one polarity to be supplied to said line wires at the end thereof remote from the first section and being effective when the stretch is conditioned to permit traffic to move from the second to the first approach section to cause coded energy of the other polarity to be supplied to said line wires at the end thereof remote from the second approach section, in combination, a coding relay located adjacent said intermediate section and controlling the supply of coded alternating current to the rails of said intermediate section and to the rails of said approach sections at the ends thereof adjacent said intermediate section, said coding relay being responsive to energy of a given polarity only, means effective when said first approach or intermediate section is occupied by a train moving from the first to the second approach section to connect said coding relay across the line wires so that the coding relay is operated by energy supplied to the line wires at the end thereof remote from the first approach section, and means effective when said second approach or intermediate section is occupied by a train moving from the second to the first approach section to connect said coding relay across the line wires so that the coding relay is operated by energy supplied to the line wires at the end thereof remote from the second section.

5. In cab signal energy supply means for use in a stretch of railway track over which may move in either direction locomotives equipped with cab signals apparatus responsive to flow of coded alternating current in the track rails, the rails of said track stretch being divided by insulated joints into an intermediate section having a first approach section at one side and a second approach section at the other side, said intermediate and approach sections each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of the approach sections remote from said intermediate section, said traffic governing apparatus being effective when the stretch is conditioned to permit traffic to move from the first to the second approach section to cause coded energy of one polarity to be supplied to said line wires at the end thereof remote from the first section and being effective when the stretch is conditioned to permit traffic to move from the second to the first approach section to cause coded energy of the other polarity to be supplied to said line wires at the end thereof remote from the second approach section, in combination, a coding relay located adjacent said intermediate section and controlling the supply of coded alternating current to the rails of said intermediate section and to the rails of said approach sections at the ends thereof adjacent said intermediate section, said coding relay being responsive to energy of a given polarity only, means effective when said first approach or

intermediate section is occupied by a train moving from the first to the second approach section to connect said coding relay across the line wires so that the coding relay is operated by energy supplied to the line wires at the end thereof remote from the first approach section while preventing flow of energy between the portions of the line wires on opposite sides of the intermediate sections, and means effective when said second approach or intermediate section is occupied by a train moving from the second to the first approach section to connect said coding relay across the line wires so that the coding relay is operated by energy supplied to the line wires at the end thereof remote from the second approach section while preventing flow of energy between the portions of the line wires on opposite sides of the intermediate section.

6. In cab signal energy supply means for use in a stretch of railway track over which may move in either direction locomotives equipped with cab signal apparatus responsive to flow of coded alternating current in the track rails, the rails of said track stretch being divided by insulated joints into an intermediate section having a first approach section at one side and a second approach section at the other side, said intermediate and approach sections each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of the approach sections remote from said intermediate section, said traffic governing apparatus being effective when the stretch is conditioned to permit traffic to move from the first to the second approach section to cause coded energy to be supplied to said line wires at the end thereof remote from the first section and being effective when the stretch is conditioned to permit traffic to move from the second to the first approach section to cause coded energy to be supplied to said line wires at the end thereof remote from the second section, in combination, a coding relay located adjacent said intermediate section, means controlled by said coding relay for supplying coded alternating current to the rails of said intermediate section, means controlled by said coding relay for supplying coded alternating current to the rails of the first or the second approach section when and only when said section is occupied by a train approaching the other approach section and the intermediate section is unoccupied, means controlled by the track relays of said first approach and intermediate sections for supplying from the line wires to said coding relay energy supplied to the line wires at the end thereof remote from said first approach section, and means controlled by the track relays of said second approach and intermediate sections for supplying from the line wires to said coding relay energy supplied to the line wires at the end thereof remote from said second section.

7. In cab signal energy supply means for use in a stretch of railway track over which may move in either direction locomotives equipped with cab signal apparatus responsive to flow of coded alternating current in the track rails, the rails of said track stretch being divided by insulated joints into an intermediate section having a first approach section at one side and a second approach

section at the other side, said intermediate and approach sections each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of the approach sections remote from said intermediate section, said traffic governing apparatus being effective when the stretch is conditioned to permit traffic to move from the first to the second approach section to cause coded energy to be supplied to said line wires at the end thereof remote from the first section and being effective when the stretch is conditioned to permit traffic to move from the second to the first approach section to cause coded energy to be supplied to said line wires at the end thereof remote from the second section, in combination, a coding relay located adjacent said intermediate section, means controlled by said coding relay for supplying coded alternating current to the rails of said intermediate section, means controlled by said coding relay for supplying coded alternating current to the rails of the first or the second approach section when and only when said section is occupied by a train approaching the other approach section and the intermediate section is unoccupied, means effective when said first approach or intermediate section is occupied by a train moving from the first to the second approach section to connect said coding relay across the line wires so that the coding relay is operated by energy supplied to the line wires at the end thereof remote from the first approach section while preventing flow of energy between the portions of the line wires on opposite sides of the intermediate section, and means effective when said second approach or intermediate section is occupied by a train moving from the second to the first approach section to connect said coding relay across the line wires so that the coding relay is operated by energy supplied to the line wires at the end thereof remote from the second approach section while preventing flow of energy between the portions of the line wires on opposite sides of the intermediate section.

8. In cab signal energy supply means for use in a stretch of railway track over which may move in either direction locomotives equipped with cab signal apparatus responsive to flow of coded alternating current in the track rails, the rails of said track stretch being divided by insulated joints into an intermediate section having a first approach section at one side and a second approach section at the other side, said intermediate and approach sections each being provided with a track circuit including a track relay, said track stretch being equipped with traffic governing apparatus for conditioning the track stretch for one direction of traffic or the other and including a pair of line wires substantially coextensive with said approach sections and over which coded energy may be transmitted between the track sections at the ends of the approach sections remote from said intermediate section, said traffic governing apparatus being effective when the stretch is conditioned to permit traffic to move from the first to the second approach section to cause coded energy to be supplied to said line wires at the end thereof remote from the first section and being effective when the stretch is conditioned

to permit traffic to move from the second to the first approach section to cause coded energy to be supplied to said line wires at the end thereof remote from the second section, in combination, a coding relay located adjacent said intermediate section and controlling the supply of coded alternating current to the rails of said intermediate section and to the rails of said approach sections at the ends thereof adjacent said intermediate section, a first directional relay which is energized when and only when the intermediate section or one of the approach sections is occupied by a train moving from the first to the second approach section, a second directional relay which is energized when and only when the intermediate section or one of the approach sections is occupied by a train moving from the second to the first approach section, means controlled by said first directional relay for connecting said coding relay across the line wires so that it is operated by energy supplied to the line wires at the end thereof remote from said second approach section.

9. In cab signal energy supply means for use in a stretch of railway track over which may move in either direction locomotives equipped with cab signal apparatus responsive to flow of coded alternating current in the track rails, the rails of said track stretch being divided into a plurality of track sections including a first and a second section each of which is provided with a track circuit including a track relay, said track stretch being equipped with traffic governing apparatus for conditioning the track stretch for one direction of traffic or the other and including a pair of line wires substantially coextensive with said first and second sections and over which coded energy may be transmitted between the track sections at the ends of said first and second sections, said traffic governing apparatus being effective when the stretch is conditioned to permit traffic to move from the first to the second section to cause coded energy to be supplied to the line wires at the end thereof remote from the first section and being effective when the stretch is conditioned to permit traffic to move from the second to the first section to cause coded energy to be supplied to the line wires at the end thereof remote from the second section, in combination, a coding relay controlling the supply of coded alternating current to the rails of said track sections, means controlled by the track relays of said sections and effective when said first section is occupied by a train moving from the first to the second section to connect said coding relay across the line wires so that the coding relay is operated by energy supplied to the line wires at the end thereof remote from the first section, and means controlled by the track relays of said sections and effective when said second section is occupied by a train moving from the second to the first section to connect said coding relay across the line wires so that the coding relay is operated by energy supplied to the line wires at the end thereof remote from said second section.

10. In cab signal energy supply means for use in a stretch of railway track over which may move in either direction locomotives equipped with cab signal apparatus responsive to flow of

5 coded alternating current in the track rails, the rails of said track stretch being divided into a plurality of track sections including a first and a second section each of which is provided with a track circuit including a track relay, said track stretch being equipped with traffic governing apparatus for conditioning the track stretch for one direction of traffic or the other and including a pair of line wires substantially coextensive with 10 said first and second sections and over which coded energy may be transmitted between the track sections at the ends of said first and second sections, said traffic governing apparatus being effective when the stretch is conditioned to permit traffic to move from the first to the second section to cause coded energy to be supplied to the line wires at the end thereof remote from the first section and being effective when the stretch is conditioned to permit traffic to move from the second to the first section to cause coded energy to be supplied to the line wires at the end thereof remote from the second section, in combination, a coding relay controlling the supply of coded alternating current to the rails of said track sections, means controlled by the track relays of said sections and effective when said first section is occupied by a train moving from the first to the second section to connect said coding relay across the line wires so that the coding relay is operated by energy supplied to the line wires at the end thereof remote from the first section while preventing flow of energy between the portions of the line wires on opposite sides of the coding relay, and means controlled by the track relays of said sections and effective when said second section is occupied by a train moving from the second to the first section to connect said coding relay across the line wires so that the coding relay is operated by energy supplied to the line wires at the end thereof remote from said second section while preventing flow of energy between the portions of the line wires on opposite sides of the coding relay.

11. In cab signal energy supply means for use in a stretch of railway track over which may move in either direction locomotives equipped with cab signal apparatus responsive to flow of coded alternating current in the track rails, the rails of said track stretch being divided into a plurality of track sections including a first and a second section each of which is provided with a track circuit including a track relay, said track stretch being equipped with traffic governing apparatus for conditioning the track stretch for one direction of traffic or the other and including a pair of line wires substantially coextensive with said first and second sections and over which coded energy may be transmitted between the track sections at the ends of said first and second sections, said traffic governing apparatus being effective when the stretch is conditioned to permit traffic to move from the first to the second section to cause coded energy to be supplied to the line wires at the end thereof remote from the first section and being effective when the stretch is conditioned to permit traffic to move from the second to the first section to cause coded energy to be supplied to the line wires at the end thereof remote from the second section, in combination, a coding relay, means governed by said coding relay for supplying coded alternating current to the rails of said first section when said first section is occupied by a train approaching said second section, means governed by said coding relay for supplying coded alternating current to the rails of said second sec-

tion when said second section is occupied by a train approaching said first section, and means controlled by the track relays of said sections and effective when said first section is occupied by a train approaching said second section to connect said coding relay across said line wires so that the coding relay is operated by energy supplied to the line wires at the end thereof remote

from the first section and effective when said second section is occupied by a train approaching said first section to connect said coding relay across the line wires so that the coding relay is operated by energy supplied to the line wires at the end thereof remote from said second section.

ARTHUR L. JEROME.
